US00D721808S

(12) **United States Design Patent**
Oi

(10) **Patent No.:** **US D721,808 S**
(45) **Date of Patent:** ** *Jan. 27, 2015

(54) **INTERVERTEBRAL IMPLANT**(75) Inventor: **Nelson Oi**, San Diego, CA (US)(73) Assignee: **NuVasive, Inc.**, San Diego, CA (US)

(*) Notice: This patent is subject to a terminal disclaimer.

Primary Examiner — Ian Simmons*Assistant Examiner* — Charles Hanson(74) *Attorney, Agent, or Firm* — Jonathan Spangler; Jennifer Russell**CLAIM**

The ornamental design for an intervertebral implant, substantially as shown and described.

DESCRIPTION

FIG. 1 is a perspective view of an intervertebral implant showing our new design;

FIG. 2 is a first side view thereof;

FIG. 3 is a second side view thereof;

FIG. 4 is a first end view thereof;

FIG. 5 is a second end view thereof;

FIG. 6 is a top view thereof; and,

FIG. 7 is a bottom view thereof.
